UNITED STATES PATENT OFFICE.

THOMAS D. MONTAGUE, OF PICTURE ROCKS, PENNSYLVANIA.

SWING.

No. 911,426.

Specification of Letters Patent.

Patented Feb. 2, 1909.

Application filed August 11, 1908. Serial No. 448,043.

To all whom it may concern:

Be it known that I, THOMAS D. MONTAGUE, a citizen of the United States of America, residing at Picture Rocks, in the county 5 of Lycoming and State of Pennsylvania, have invented new and useful Improvements in Swings, of which the following is a specification.

This invention relates to swings, and one 10 of the principal objects of the same is to provide a swing of simple construction which will be provided with means to prevent children from falling from the seat during the operation of the swing.

Another object of the invention is to provide a swing in which the suspending ropes 15 will be connected to the seat and extend through the bar for supporting the back and through the side arms and front bars 20 means being provided for preventing the parts of the swing from becoming displaced in use.

These and other objects may be attained by means of the construction illustrated in 25 the accompanying drawing, in which,—

Figure 1 is a side elevation of a pair of swings made in accordance with my invention and having supported therefrom a platform or foot rest. Fig. 2 is a perspective 30 view of a modified form of my invention. Fig. 3 is a detail elevation of one of the platform supports broken away in the center. Fig. 4 is a detail section illustrating the manner in which the lower bar of the 35 back is pivoted to the side bars of the seat. Fig. 5 is a detail view in partial section, showing the manner of securing the upper cross bar of the back to a strand of the supporting rope. Fig. 6 is a detail in partial 40 section, showing the balls or spheres through which the supporting rope passes to space the bars apart and to hold them in operative positions.

Referring to the drawing, the numeral 1 45 designates the seat of the swing comprising side bars 2 and cross slats 3, said slats being secured at proper distances apart by nails, screws or other fastenings. The back of the seat consists of the cross bar 4 provided with 50 end pintles 5 mounted in sockets in the side bars 2, as shown more particularly in Fig. 4. Connected to the cross bar 4 are the upright members 6, the upper cross bar 7 being connected to the upright 6 by suitable fastenings 8. The side arms 9 are supported 55 at their rear ends upon the cross bar 7, and

in front a guard bar 10 rests upon the ends of the side arms.

The suspending rope 11 extends through the side arms, the cross bar 7 and the side 60 bars 2 at the back of the swing, and knots 12 are formed in the ends of the rope to sustain the weight of the swing. The suspending rope in front extends through the guard bar 10, the side arms 9 and the front 65 cross slat of the seat and through the side bars 2, the ends of the rope being knotted, as previously mentioned.

Upon reference to Fig. 1 it will be seen that the suspending ropes at the front and 70 back of the seat are brought together at the point 13 and are connected to single strands 14 provided with hooks 15 designed to engage screw eyes on a suitable support. The ropes 11 may each comprise a single strand, 75 and the supporting members 14 may be connected at the required point to balance the swing.

In order to hold the side arms, the rear 80 cross bar and the guard bar 10 in proper relative relation to the seat, I have provided a series of balls or spheres 16 having holes extending through the same to accommodate the ropes 11, as shown in Fig. 6, and these balls or spheres may be arranged as shown 85 in Fig. 1.

As shown in Fig. 5, the cross bar 7 is connected to the rope 11 by means of a nail or pin 17, and the balls or spheres 16 are omitted.

A detachable platform or foot rest is shown in Fig. 1 and consists of side bars 18 connected by slats 19, said side bars 18 being supported upon metal yokes comprising cross bars 20 and upright arms 21, said arms 95 terminating in hooks 22 designed to engage the side bars 2 of the swing between the slats 3, as illustrated in Fig. 1.

From the foregoing, it will be obvious that a swing made in accordance with my invention may be composed almost entirely of rounds, and that the construction is simple and efficient for its purpose, means being provided to prevent children from falling out of the swing.

I claim:

1. A swing comprising a seat composed of side bars, cross members connecting said side bars, a back pivoted to said side bars, a cross bar connected to the back, side arms having their ends adjacent the ends of the cross bar at the back, a guard bar resting upon

said side arms at the front, flexible suspending devices extending through said side arms and cross bars, and connected to said seat, and means for holding the side arms and 5 cross bars spaced from said seat.

2. A swing comprising a seat composed of side bars and cross slats, a back pivoted to the side bars, a cross bar connected to the back, side arms resting upon said cross bar 10 at the back, a guard bar resting upon said side arms at the front, suspending ropes ex-

tending through said bars and provided with knots for supporting the swing, and balls through which said suspending rope extends, said balls serving to hold the parts of the 15 swing in proper relative positions.

In testimony whereof I affix my signature in presence of two witnesses.

THOMAS D. MONTAGUE.
